UNITED STATES PATENT OFFICE.

DUDLEY BAIRD, OF BERKELEY, CALIFORNIA, ASSIGNOR TO GENERAL CHEMICAL COMPANY, OF NEW YORK, N. Y., A CORPORATION OF NEW YORK.

SHAFT FOR ROASTING-FURNACES.

1,262,432.

Specification of Letters Patent.

Patented Apr. 9, 1918.

Application filed July 3, 1915. Serial No. 37,874.

To all whom it may concern:

Be it known that I, DUDLEY BAIRD, a citizen of the United States, and a resident of Berkeley, California, have invented certain 5 new and useful Improvements in Shafts for Roasting-Furnaces, of which the following, taken in connection with the accompanying drawings, is a specification.

My invention relates to furnaces, especially such as are used for roasting ores, and such as are provided with superposed stationary hearths upon which the ore is stirred and distributed by rakes or plows affixed to arms, said arms being in turn affixed to and 15 rotatable with a central vertical shaft which extends through central apertures in the hearths and is rotated by any suitable mechanism.

More particularly my invention relates to 20 the central, rotatable shafts of such furnaces, of the type in which longitudinally disposed passages are provided for conducting a cooling medium to and from the rabble arms through a plurality of longitudinally spaced 25 and angularly disposed sets of rabble arm inlet and outlet ports or apertures, and an object of my invention is to produce a shaft in which the passages are provided by partitioning the hollow shell of the shaft longitudinally, the partitioning means extending substantially parallel with the shaft and extending between and separating the inlet and outlet ports of each of said sets. Another object of my invention is to produce a 30 hollow shaft having rabble arm inlet and outlet ports and having a non-diametral partition by which the shaft is divided into unequal cross-sectional portions, said partition extending between and separating said 35 ports. Other objects of my invention will be pointed out or will otherwise appear in the following description of an embodiment of my invention in which—

Figure 1 is a longitudinal sectional view 40 on the line 1—1 of Fig. 2, and

Fig. 2 is a cross-section on the line 2—2 of Fig. 1.

The shaft illustrated is composed of longitudinal articulating sections of which two 45 only are shown in Fig. 1. Each section consists of an outer cylindrical shell 3, provided with rabble arm inlet ports 4 and rabble arm outlet ports 5, the adjacent ports 4, 5 constituting a set through which a cooling medium is conducted to and from each rab-

ble arm 6, and the set or sets of ports in one horizontal plane being angularly disposed, as shown, at right angles, with reference to the set or sets in a plane longitudinally spaced from the first mentioned plane. The 60 rabble arms are, of course, provided with the usual channels for the cooling medium and are secured to the shaft in any suitable and well known manner. The rabble arms of one horizontal plane are adapted to move 65 material on one of the furnace hearths while the rabble arms thereabove and extending at right angles to the first mentioned arms are adapted to move material on the hearth immediately above the first mentioned hearth. 70

Secured within the shaft, and dividing it into two side, longitudinal passages 7 and a central, longitudinal passage 8 are two similar partitions or vanes 9, which extend parallel with the shaft and the edges of which 75 extend between the ports 4, 5 of each set and separate them so that each port 4 is in communication with one of the passages 7 and each port 5 is in communication with the central passage 8. The partitions extend across the shaft preferably in the form 80 of an arc and the edges of each partition are, as shown, 90° apart, one edge extending between and separating the ports 4, 5 of one set and the other edge extending between 85 and separating the ports 4, 5 of another set which is longitudinally spaced from and angularly disposed with reference to the ports 4, 5 of the first mentioned set. The partitions are preferably arcuate in form so 90 as to withstand the stresses of unequal expansion without danger of shearing. The partitions, which may be cast integrally with the shell or formed separately and then secured to said shell, divide the shaft into two 95 channels 7 adapted for the passage of cooling medium before it has become heated and the central channel 8, adapted for the passage of the cooling medium after it has traversed the rabble arms and has therefore become 100 heated and expanded, and are constructed, as shown and described, so that the combined cross-sectional areas of the channels 7, is less than the cross-sectional area of the channel 8, thus providing a substantially constant 105 velocity of the cooling medium in the shaft channels.

In the operation of the furnace a suitable cooling medium is conducted into the passages 7 from which it passes through the 110

various inlet ports 4 into the arms, after traversing which it passes through the outlet ports 5 and enters the central passage 8 and finally escapes from said passage at the end thereof, the cooling medium being continuously circulated in this way.

I claim:

1. A hollow shaft comprising an outer shell provided with a plurality of longitudinally spaced and angularly disposed sets of rabble arm inlet and outlet ports, the ports of a given set being angularly disposed in the same horizontal plane, and a non-diametral partition therein extending substantially parallel with the shell and having its opposite edges extending between and separating the ports of said sets, said partition being uniformly spaced from the shell wall so as to constitute therewith a chamber of uniform cross section throughout the length of the partition.
2. A hollow shaft comprising an outer shell provided with a plurality of longitudinally spaced and angularly disposed sets of rabble arm inlet and outlet ports, the members of a given set being angularly disposed in the same horizontal plane, and a non-diametral arcuate partition therein extending substantially parallel with the shell and having its opposite edges extending between and separating the ports of said sets, said partition being uniformly spaced from the shell wall so as to constitute therewith a chamber of uniform cross section throughout the length of the partition.
3. A hollow shaft comprising an outer shell provided with a plurality of longitudinally spaced and angularly disposed sets of rabble arm inlet and outlet ports, the members of a given set being angularly disposed in the same horizontal plane, and a non-diametral inwardly convexed partition therein extending substantially parallel with the shell, opposite edges of said partition extending between and separating the ports of said sets.
4. A hollow shaft comprising an outer shell with two pair of sets of rabble arm inlet and outlet ports, the members of a given

set being also angularly disposed in the same horizontal plane and the sets of a given pair being angularly separated not to exceed 90°, and a pair of non-diametral partitions therein extending substantially parallel to the shell, one edge of each partition extending between and separating the ports of certain sets of a pair and the opposite edge of said partition extending between and separating the ports of the remaining sets of the same pair.

5. A hollow shaft comprising an outer shell with two pair of sets of rabble arm inlet and outlet ports, the members of a given set being also angularly disposed in the same horizontal plane and the sets of a given pair being angularly separated not to exceed 90°, and a pair of non-diametral partitions therein extending substantially parallel to the shell, one edge of each partition extending between and separating the ports of certain sets of a pair and the opposite edge of said partition extending between and separating the ports of the remaining sets of the same pair, the combined cross sectional area of the passages formed between the partitions and the shell being less than the cross sectional area of the passage formed between the two partitions.

6. A hollow shaft comprising an outer shell provided with a plurality of longitudinally spaced sets of rabble arm inlet and outlet ports, the ports of a given set being angularly disposed in the same horizontal plane, and a longitudinal partition therein extending substantially parallel with the shell and dividing the shell into two parallel and continuous longitudinal chambers of unequal cross section, opposite edges of said partition extending between and separating the ports of said sets.

In testimony whereof I have hereunto set my hand in the presence of two subscribing witnesses.

DUDLEY BAIRD.
